UNITED STATES PATENT OFFICE

2,552,120

PROCESS FOR DRYING MACARONI

Bayard S. Scotland, Joliet, Ill.

Application November 1, 1949, Serial No. 124,897

7 Claims. (Cl. 34—31)

1

This invention relates to a new and improved process and apparatus for drying macaroni and other articles from which it is desired to remove moisture.

Drying of macaroni has long been a problem because of the length of time involved. In making macaroni it is extruded from dies when in a moist state throughout. From years of experience men in the macaroni industry have drawn one definite conclusion and that is that macaroni must be allowed to dry naturally or it would not be top quality. There have been numerous attempts to speed up the drying of macaroni, but the result has always been a poorer grade of macaroni. Ordinarily macaroni "checks" and cracks on the application of heat. Thus enormous storage space has been required in order to carry on the production of macaroni.

It is therefore a principal object of this invention to effect a relatively quick continuous drying of top quality macaroni.

An important object of this invention is the provision of means in a drying mechanism for preliminarily drying the outer surface of moist macaroni and other articles and thereafter driving out internal moisture by a succession of passes through ovens and a sweat box.

Another important object of this invention is to provide a process of drying macaroni and other articles such as cereals and including corn wherein the moisture is effectively removed quickly and economically without impairing the quality of the articles.

Still another important object of this invention is to supply infra-red heat rays in the drying of articles such as macaroni.

Another and further important object of this invention is the provision of means in a drying process and apparatus for continuously removing moist air from the presence of the articles being dried as they pass through the various stages of drying.

Another and still further important object of this invention is to provide a process and apparatus for drying macaroni or the like in which several ovens are employed and employing various conditions of air circulating therein.

Still another and further important object of this invention is the provision of means in a drying process to regulate the temperature of various ovens and the time through which articles are kept in these ovens.

Another important object of this invention is to provide a continuous process for drying moist macaroni without "checking" through a predetermined series of steps including a preliminary drier, an oven, a sweat box, another oven, and finally cooling at room temperature.

Another object of this invention is the provision of an oven having an infra-red heating means and arranged to employ the heating means to pre-heat air to be subsequently circulated over

2

the articles being dried as they pass through the oven.

Other and further important objects of this invention will become apparent from the disclosures in the following specification and accompanying drawings.

In the drawings:

Figure 1 is an elevational view of the drying apparatus partially in schematic form.

Figure 2 is a top plan view of the preliminary drier as used in this apparatus.

Figure 3 is a sectional view taken on the line 3—3 of Figure 2.

Figure 4 is a top plan view of the first oven of this apparatus.

Figure 5 is a sectional view of the oven taken on line 5—5 of Figure 4.

Figure 6 is a sectional view of the sweat box taken on line 6—6 of Figure 1.

Figure 7 is a top plan view of the second oven employed in this dryer.

Figure 8 is a sectional view taken on the line 8—8 of Figure 7.

As shown in the drawings:

The reference numeral 10 indicates generally a preliminary drier or a heating unit having a trough-like container 12, with a conveyor 14 of screen material running therethrough. The conveyor is of the endless type and is adapted to carry material through the trough 12 from one end to the other. The preliminary drier is equipped with a heating unit 16, preferably of the infra-red type and capable of attaining a heat of approximately 150° F. Although 150° is the desired temperature, the preliminary drier will operate effectively throughout a range of temperatures from 100 to 200° F. The preliminary drier is adapted to be hung by hanger brackets 20 from the ceiling 18 of the room in which the drying apparatus is installed. The brackets depend from the ceiling 18 and extend around the bottom of the trough 12 holding it in fixed position with respect to the ceiling. The preliminary drier is equipped with an inlet 22 and an outlet 24. Macaroni or other material to be dried is delivered to the preliminary drier through the inlet 22 and thereupon the material is moved by means of the conveyor 14 along the trough 12. The macaroni is simultaneously heated by the heating unit directing its infra-red rays down on the conveyor. During the travel of the moist macaroni or other material such as corn or the like, a fan 26 is adapted to direct air from the room over the material carried by the conveyor. Thus especially in the case of macaroni which is wet throughout, an outer surface or shell-like material is formed on the outside permitting subsequent heat treatment and handling without fear of the material sticking to ovens or other devices through which the material is to be passed. The preliminary drier is more or less a flash means for quickly heating the macaroni and forming this outer shell.

and doing it in a relatively short period of time. It has been found that a $1\frac{1}{2}$ minutes time period for the material to travel through the preliminary drier is sufficient to dry the outer surface of the material and still eliminate any checking or cracking which has ordinarily accompanied quick drying of material such as macaroni. Although it is believed that $1\frac{1}{2}$ minutes is the most desirable period of time in which the material is to be in the preliminary drier, it is believed that a range of from a minute to two minutes is acceptable and under certain conditions other particular times within that range might prove to be more desirable.

It has been deemed advantageous to describe the complete process of the macaroni drier without immediately delving into the details of construction of each individual portion of the apparatus and thus we shall continue throughout the process and thereafter return to the more specific details of construction of the preliminary drier and also the following elements. The macaroni, after it has been flash dried in the preliminary drier, is discharged at the outlet 24 and passes downwardly through a conduit 28 to a first oven 30. The oven includes a deep tray-like container 32 and similarly to the preliminary drier has a heating unit 34 of the infra-red type capable of attaining a heat of 250° F. As in the case of the preliminary drier 10 the first oven 30 may have a heat from 200° to 300° F., and still produce an acceptable drying of the macaroni. The 250° has been found to be very desirable, but under certain conditions and sizes of the macaroni some other temperature within this acceptable range of 200 to 300° might be employed. This first oven 30 is equipped with a vibrator means 36, which by means of electricity causes the tray 32 to vibrate at any desired frequency to thereby cause the macaroni or other articles being dried to move from one end of the tray to the other. It should of course be understood that any type of conveyor means may be employed in this first oven, and an endless conveyor of the type employed in the preliminary drier or the slatted type conveyor employed in a subsequent oven are equally acceptable. In order to complete the mounting of the oven on the vibrator means 36, a spring mounting 38 at the other end of the tray 32 is required. The spring 38 is carried on a floor engaging leg 40. The floor of the room is designated by the numeral 42 and thus the oven 30 is supported on the floor. The oven 30 is equipped with an inlet 44 into which the conduit 28 passes material to be dried. The vibrator 36 is set in motion and the material is moved along the tray 32 to an outlet 46. The desired length of time for the material to be in the first oven 30 is $5\frac{1}{2}$ minutes. However, by experiment it has been found that the range of successful operation is from 4 to 7 minutes, and it is therefore a particular object of this invention to include in the coverage thereof the entire range of successful drying operation. It will be recalled that in the preliminary drier air was circulated over the material lying on the screen conveyor and that this air passing over the macaroni was air at room temperature. In the first oven air is drawn in over the infra-red heating unit designated by the numeral 34 and after being pre-heated it is then blown down over the material in the deep tray 32 all by means of the combination fan and blower 48.

The material being dried, and in this case the macaroni, passes from the outlet 46 of the first

oven and is discharged into an enclosed sweat box 50. The sweat box is mounted on floor engaging legs 52 and is equipped with a canvas conveyor 54 which runs the length of the box at a very slow speed. The macaroni is deposited at an inlet 56 and drops onto the conveyor 54 whereupon it is moved over a period of time to a discharge or outlet spout 58. The enclosed sweat box performs the function attributed to it by its name. The macaroni is permitted to sweat from the great heat applied in the first oven 30 and the moisture comes to the surface of the macaroni. The length of time in the sweat box is preferably 20 minutes. However, it has been found through experiment that a range of time limits from approximately 10 minutes to 30 minutes is acceptable.

The macaroni, upon discharging from the outlet 58 of the sweat box, drops into a hopper 60, forming part of a blower and elevator mechanism. A blower 62 is adapted to force a current of air upwardly to an elevating conduit 64 which has communication with the hopper 60 in such a manner that the macaroni is carried upwardly through the conduit 64 on a current of air and deposited in a cyclone 66. The cyclone is a device for settling material entering therein with a mass of air. It is similar in effect to an expansion valve and thus the air is permitted to escape to an outlet in the top thereof and the heavier macaroni drops downwardly through a central portion thereof.

A second oven, 68, is provided with a slatted conveyor 70 and a heating unit 72 in the same manner as the preliminary drier and the first oven. Hangers 74 support the second oven from the ceiling 18. The second oven is further provided with an inlet 76 disposed immediately below the cyclone 66 and an outlet at the far end of the conveyor 70 as shown at 78. The heating unit is again of the infra-red type and is adapted to produce heat of approximately 250° F. Here again an acceptable range of temperatures is designated as from 200 to 300° F. The speed of the slatted conveyor 70 is similar to the speed of the vibrating conveyor of the first oven. It thus requires $5\frac{1}{2}$ minutes for the slatted conveyor 70 to move macaroni received at the inlet 76 to the outlet 78. This period of time may vary throughout an acceptable range of 4 to 7 minutes. In the case of this second oven there is no air circulation permitted over the macaroni as it is carried through this oven and in this respect it differs from both the preliminary drier and the first oven.

Upon completion of this cycle of operation the macaroni is now completely dried. However, it must be cooled in the following manner in order to eliminate spoilage that might be occasioned if it were to be immediately packaged. Thus the outlet 78 of the second oven is directly above a first trough 80, which is exposed to the room in which the drying occurs, and is equipped with a conveyor 82 of the endless type adapted to run from one end of the trough to the other, and deliver macaroni from the inlet 84 to an outlet 86 at the end thereof. It should be understood that this conveyor 82 carries the heated macaroni from one end to the other thereof exposed to room atmosphere in order to facilitate cooling or bringing of the temperatures of the macaroni down to room temperature prior to packaging. The macaroni when it is discharged from the outlet 86 of the first trough 80 falls into a second trough 88 having an endless conveyor 90 prefer-

ably of the canvas type, which runs from one end to the other of the trough 88. The macaroni falls into the inlet 92 and is discharged at the outlet 94. Here again the conveyor is open to room atmosphere and thus permits the macaroni to cool and come down to the temperature of the room. The second trough 88 is mounted on floor engaging legs 96 and the first trough is carried on the second trough by means of spaced supports 98. The total length of time in which the macaroni is on the conveyors 82 and 90 for most efficient cooling has been found to be twenty minutes. But, here again it is possible to vary the length of time throughout a range of from 10 to 30 minutes without adverse effects and still effect a cooling of the macaroni to the required degree. The spout-like outlet 94 is used to direct material dried to packages or the like for storage or for later sale. The macaroni thus dried is free of checking and free of harmful moisture which would cause spoilage if the macaroni were improperly dried.

The success of this drier has been accomplished by the employment of a suction means designated by the numeral 100 which hangs from the ceiling 18 by hanger brackets 102. The suction means is adapted to remove air and particularly moist air from the vicinity of the entire drying apparatus. Thus as the macaroni or other material being dried passes through the various stages of the drying mechanism, moist air that is driven from the macaroni is drawn from the room immediately upon its discharge from the macaroni and thus the atmosphere in which the drying takes place is relatively free of moisture loosened or freed from the macaroni. This of course is conducive to a minimum of reattraction of the moisture for the macaroni through the last stages of the drying apparatus and particularly the second oven and the cooling room conveyors 82 and 90.

In order to more particularly designate the elements of this drying apparatus legends have been incorporated on Figure 1 of the drawings in order to designate particular elements and arrows have been employed to show the path of travel of the macaroni during its drying operation.

Figures 2 and 3 show in detail the construction of the preliminary drier designated by the numeral 10 in Figure 1. The screen conveyor 14 is maintained in spaced apart position by rollers 104 and 106 journaled for rotation, in extreme ends of the preliminary drier trough-like container 12. Throughout the drawings there has been no means shown to drive the endless conveyors or fans and it should be explained that external motor means or belting from some power source is provided to impart proper rotation and drive to these elements. In the case of the preliminary drier the conveyor 14 composed of screen or grid material moves from a position adjacent the inlet 22 along the pan 12 to the outlet 24. Thus material entering the inlet drops on to the mesh conveyor and is carried thereby to the discharge of the preliminary drier. During its travel along this pan 12 the material, and in this case macaroni, is subjected to forced currents of air at room temperature. The pan or trough 12 is provided with lateral side conduits 108 and 110. The conduit 108 is provided with a series of spaced openings 112 entering the trough 12 over the conveyor 14. The fan 26 joins the conduit 108 as shown in Figures 2 and 3, and draws air at room temperature therein and disperses it along the conduit 108 whereupon it is

discharged through the openings 112 on to the top of the conveyor 14. The corresponding conduit 110 on the opposite side of the tray 12 is similarly equipped with spaced apertures 114 which are offset from the openings 112 in the conduit 108, whereupon currents of air entering at 112 are required to move longitudinally of the drier in order to find one of the air outlets 114 in the elongated lateral side conduit 110. As best shown in Figures 2 and 3 the fan is provided with an opening 116 to the room atmosphere in order to draw air therein. The discharge of the air after it passes over the macaroni to be dried is out the ends 118 of the conduit 110. It should thus be realized that the air passing over the macaroni in the preliminary drier is air in which the moisture is continuously removed by reason of the suction means 100. This is conducive to quick extraction of surface moisture on the macaroni. The preliminary drier is therefore primarily for the purpose of removing surface moisture and conditioning the macaroni for future more intense heating and drying of the interior thereof.

The first oven 30 has its heating unit 34 divided into upper and lower chambers by means of a partition 120 disposed intermediate the top and bottom of the heating unit 34. The upper chamber formed by the partition 120 is designated by the numeral 121 and is open at one end of the first oven 30 at 122 for admission of room air therethrough. The chamber 121 is thus partially heated by the upper sides of the infra-red heating unit. The combination fan and blower 48 is adapted to draw air through the opening 122. A conduit 124 completes the path of travel from the air inlet 122 through the chamber 121 to the fan and blower 48 as best shown in Figure 4. The drawing of air at room temperature through the chamber 121 causes the air to be pre-heated and in the combination fan and blower the pre-heated air is forced outwardly through the V-shaped conduit 126, thus delivering this preheated air to laterally spaced side conduits 128 and 130. The V-shaped conduit 126 directly joins the cross conduit 132 which has communication with both of the side conduits 128 and 130. As the pre-heated air is passed down the side conduit 128 it is discharged through longitudinally spaced nozzles 134, thus directing hot air over the macaroni moving through the deep tray 32 of the first oven 30. Similarly spaced nozzles 136 offset from the nozzles 134 are located in the conduit 130 and direct hot air onto the macaroni in the deep tray 32 from the opposite side. The first oven thus distinguishes materially from the preliminary drier, first in that the temperature is considerably higher, and second, the macaroni is maintained within the oven for a considerably longer period of time, and third, the currents of air directed over the macaroni to be dried is pre-heated, and thus in combination with the infra-red type of heating unit the macaroni is dried or heated on the inside, tending to draw and drive moisture out from the interior of the macaroni pieces. The detailed construction of the first oven as just described is shown in Figures 4 and 5.

Figure 6 shows a sectional view of the sweat box employed in this apparatus immediately following exit of the macaroni from the first oven. The conveyor 54 is of the endless canvas type and is provided with spaced rollers 138 and 140 over which the canvas is draped for proper spacing and driving thereof. The rollers are journaled

within the sides of the sweat box 50. The sweat box is provided with a top 142 hinged at 144 to permit access to the interior thereof. However, in operation the sweat box remains closed and the macaroni is permitted to sweat so that the heat imparted thereto by the first oven causes the internal moisture to come to the outer surface.

The macaroni then drops into the hopper 60 from the enclosed sweat box and the blower 62 carries the macaroni on a cushion of air up through the conduit 64 to the cyclone 66. Inasmuch as the macaroni was permitted to sweat or have its moisture come to the surface, this air by which the material is blown upwardly to the cyclone tends to drive off portions of the surface moisture and when the macaroni drops from the cyclone to the second oven it is ready to assume or assimilate the heat provided by the infra-red heating unit 72. The second oven is best shown in Figures 7 and 8, in which the conveyor 70 is provided with spaced rollers 146 and 148. These rollers are equipped with laterally spaced sprockets 150 and 152 over which the slatted conveyor 70 is adapted to be run and driven. Cross bars 154 join chain elements of the conveyor 70 and cooperate with the bottom 156 of the tray or elongated pan of the second oven and thus act as an undershot feeder for delivering macaroni from one end of the oven to the other. Various types of conveyors have been shown in the preliminary drier and the first oven as well as the enclosed sweat box. It should be understood that any one type of conveyor may be effectively employed or several types may be employed as shown without interfering with the successful operation of the entire apparatus.

The device thus described is a new apparatus for the effective drying of macaroni without impairing the quality thereof. Further, the drier may be employed for drying cereals such as corn in the same manner. In the drying of articles which do not have excessive surface moisture the preliminary drier might possibly be eliminated. The device of this invention has been found to be particularly effective in the drying of corn following its picking from the field. In order to store corn or other grains safely it is necessary that its moisture content be some predetermined maximum and if it is above that amount when picked when it is necessary to dry the corn artificially by means such as the drier of this invention. The corn reacts in the same manner as the macaroni and although it is not necessary to employ the preliminary drier in the drying of corn, the remainder of the apparatus and process is identical.

Numerous details of construction may be varied throughout a wide range without departing from the principles disclosed herein, and I therefore do not propose limiting the patent granted hereon otherwise than as necessitated by the appended claims.

What is claimed is:

1. A macaroni drying process comprising the steps of preliminarily heating macaroni to be dried at a temperature range of 100 to 200° F. for a period of one to two minutes, heating the preliminarily heated macaroni at a temperature range of 200 to 300° F. for a period of four to seven minutes, thereafter passing the macaroni to be dried through an enclosed sweating chamber for a period of ten to twenty-five minutes, and then heating the macaroni to be dried at a

75

temperature range of 200 to 300° F. for a period of four to seven minutes.

2. A macaroni drying process comprising the steps of preliminarily heating macaroni to be dried at a temperature range of 100 to 200° F. in an atmosphere of moving room air for a period of one to two minutes, heating the preliminarily dried macaroni at a temperature range of 200 to 300° F. in an atmosphere of moving pre-heated air for a period of four to seven minutes, thereafter passing the macaroni to be dried through an enclosed sweating chamber for a period of ten to twenty-five minutes, and then heating the macaroni to be dried at a temperature range of 200 to 300° F. in an atmosphere of stationary air for a period of four to seven minutes.

3. A process as set forth in claim 2 in which a suction is placed on the room in which the drying occurs whereby moist air is continuously withdrawn from the presence of the drying macaroni.

4. An article drying apparatus comprising a preliminary drier maintained at temperatures between the range of 100 to 200° F., means for passing articles to be dried through said preliminary drier over a period of about one to two minutes, an oven maintained at temperatures between the range of 200 to 300° F., means for moving articles to be dried from said preliminary drier through said oven over a period of about 4 to 7 minutes, an enclosed sweat box for said articles to be dried, means for moving articles to be dried from said oven through said sweat box over a period of about 10 to 25 minutes, a second oven maintained at temperatures between the range of 200 to 300° F., and means for moving said articles to be dried from said sweat box through said second oven over a period of about 4 to 7 minutes.

5. An article drying apparatus comprising a preliminary drier, heating means therefor, a conveyor in said preliminary drier adapted to convey articles therethrough, fan means arranged and constructed to circulate room air through said preliminary drier, a first oven, heating means therefor, means for conveying articles through said first oven, suction means for drawing room air over said first oven heating means separable from said articles for preheating said air, and means for blowing said preheated air over the articles within said first oven, an enclosed sweat box, a conveyor for carrying articles through said sweat box, a second oven, heating means therefor, and a conveyor in said second oven for moving articles therethrough.

6. An apparatus as set forth in claim 5 in which suction means is positioned adjacent the apparatus and arranged and constructed to continuously take moist air away from the presence of the drying apparatus.

7. An apparatus as set forth in claim 5 in which combination blower and cyclone means is provided for delivering articles from the sweat box to the second oven.
